US0D1104452S

(12) **United States Design Patent** (10) **Patent No.:** **US D1,104,452 S**
(45) **Date of Patent:** **** Dec. 9, 2025**

(54) **KEYRING**

(71) Applicant: **Abraham Franco**, Miramar, FL (US)

(72) Inventor: **Abraham Franco**, Miramar, FL (US)

(**) Term: **15 Years**

(21) Appl. No.: **29/966,002**

(22) Filed: **Sep. 30, 2024**

(51) **LOC (15) Cl.** **03-01**

(52) **U.S. Cl.**

USPC **D3/211**

(58) **Field of Classification Search**

USPC D3/201, 207-212, 234, 248, 270, 271.1,
